UNITED STATES PATENT OFFICE.

ARCHIBALD NIELD, OF MANCHESTER, ENGLAND, ASSIGNOR OF ONE-HALF TO GEORGE HENRY WATTS BLICK, OF MANCHESTER, ENGLAND.

CLOSURE FOR FOOTBALL CASES AND OTHER ARTICLES CONTAINING AN INFLATABLE AIR BAG OR THE LIKE.

Application filed May 8, 1923. Serial No. 637,501.

To all whom it may concern:

Be it known that I, ARCHIBALD NIELD, a subject of the King of Great Britain and Ireland, and a resident of Manchester, in the county of Lancaster, England, have invented certain new and useful Improvements in or Relating to Closures for Football Cases and Other Articles Containing an Inflatable Air Bag or the like, of which the following 10 is a specification.

This invention has reference to closures for football cases and like articles containing an inflatable air-bag or the like, and to closures of the kind consisting of a cap or disc adapted to be fitted in an opening in the football case or other article.

The object of the present invention is to provide an improved closure of the kind referred to which will be simple and efficient in use.

According to this invention the opening in a football case or other article, through which the air-bag or the like and/or the inflation nozzle or equivalent thereof is inserted and withdrawn, is closed by a cap or disc provided on its inner side with a flexible peripheral flange, which when the cap or disc is pressed into the opening engages behind the periphery thereof or the like where 25 it is clamped by the inflation of the air-bag or the like. The cap or disc may be provided with means, e. g. a plug, for closing the inflation nozzle or equivalent of the air-bag or the like, or it may have provided in 30 it a hole through which the nozzle or the like can be drawn for inflation, and this hole and the nozzle may be closed by a plug having a peripheral flange, similar to that of the cap or disc, which engages behind the 35 periphery of the hole in the cap or disc. Alternatively, a separate hole may be provided in the case or other article for the drawing out of the nozzle or the like, and such hole and the tube or the like may be 40 closed by a plug as just described.

In the accompanying drawings Fig. 1 is a fragmentary section of a football, the case of which is provided with one form of closure in accordance with the invention, and 50 Fig. 2 is a perspective view of the closure removed. Fig. 3 is a similar view to Fig. 1 illustrating an arrangement of case closure in which the latter is provided with means for closing the end of the inflation

nozzle of the bladder, and Fig. 4 is a like 55 view to Fig. 3 illustrating a modification thereof. Fig. 5 is also a fragmentary section of a football showing a further modification of the means for closing the bladder inflation nozzle. Fig. 6 is a like view to 60 Fig. 1 illustrating a form of closure permanently secured to the case, and Fig. 7 is a plan of the closure.

In the drawings and the following description like characters of reference indicate like parts.

Referring first to Figs. 1 and 2 of the drawings, according to this way of applying the invention to a football case, to which it is especially applicable, the case 8 is provided with a circular opening 9 of appropriate size to permit of the ready insertion and removal of the bladder 10. The periphery of the hole 9 may be strengthened against stretching by a leather washer 11 70 secured on the inside of the case, or by any other appropriate means, and in conjunction with the hole there may, if desired, be provided the usual inner flap or tongue (not shown).

For closing the opening 9 in the case we provide a cap or disc of leather, canvas-backed rubber or other suitable material 12, provided with a peripheral flange 13 of sufficient flexibility to permit of its being forced 80 through the opening 9 when the cap or disc is pushed thereinto.

To close the opening 9 in the case 8 after the bladder 10 has been inflated and the inflation nozzle 14 sealed and pushed back into the case in the ordinary way, the cap or disc 12 is fitted to the opening 9 and pressed inwards until its peripheral flange 13 slips through the opening 9 when on the release 90 of the pressure the flange 13 is clamped between the case 8 and the bladder 10, or between the case and the flap or tongue, when such is employed, by the pressure of inflation and secures the cap or disc 12 in position.

When, as illustrated, the bladder inflation 100 nozzle 14 of the kind which is normally introverted or sheathed within itself so as not to project beyond the periphery of the bladder and is adapted to be drawn out into a projecting position for inflation, the cap or disc 12 may, as shown in Fig. 3, be provided on its inner side with a plug 15 adapted to enter and seal the inflation

2

nozzle. Conveniently the plug 15 may be attached to the cap or disc 12 by being formed with a flanged head 15^a which is secured between the cap or disc 12 and the disc of material which forms the peripheral flange 13, and is secured to the cap or disc 12. With such arrangement of closure, after distention of the bladder 10, the plug 15 on the cap or disc 12 is inserted into the inflation tube 14, which may be further sealed by a rubber band or a ligature 16, and the cap or disc pressed inwards when the projecting portion of the inflation tube is introverted or sheathed and the peripheral flange 13 of the cap or disc 12 passes through the opening 9 in the case 8 and is secured as before.

In conjunction with the plug 15 there may be provided an annular flange 17 adapted to pass over the outer end of the inflation nozzle and lie between same and the inner part of the nozzle when the latter is introverted or sheathed, as shown in Fig. 4.

Instead of providing the sealing plug 15 on the cap or disc 12, the plug may be formed separately as shown in Fig. 1 in which case the plug will be fitted to the nozzle 14 and the latter will be introverted or sheathed before the cap or disc is fitted. Or and as shown in Fig. 5 the cap or disc 30 may be formed with a hole 18 through which the nozzle 15 can be withdrawn for inflation. In this case the head of the plug may serve to close the hole 18 in the cap or disc 12 and be provided with a peripheral flange 35 19, similar to the flange 13 of the cap or disc, to engage behind the cap or disc and secure the plug in position. Alternatively, a hole may be provided at another part of the case 8 for the drawing out of the inflation tube and the latter may be sealed and the hole closed by a flanged plug, as just described.

According to the modification illustrated in Figs. 6 and 7, the disc or cap 12 may be attached to the case on the inner side thereof by an elastic strip or strips 20 which will permit of the cap or disc being removed from the opening 9 and moved to one side for the insertion and inflation of the bladder 50 10, and will assist in securing the cap or disc when fitted in position. When the peripheral flange 13 of the cap or disc 12 is made of rubber, the strip or strips 20 may be constituted by extensions thereof, the 55 ends of the extensions being, if necessary, suitably strengthened, such as by gauze, for their attachment for stitching or otherwise to the case 8. In this arrangement, also, the plug 15 may be provided on the cap or disc 60 12.

Although the invention has been exemplified in its application to football cases, it will be understood that the invention is equally applicable to other cases or articles containing an inflatable air-bag or the like.

What I claim as my invention and desire to secure by Letters Patent is:—

1. In combination with an inflatable bag and a casing therefor having a circular opening therein, a closure for said opening comprising a circular disc part to close said opening, and on the disc part at its inner side a peripheral flange part flexible throughout so as to be yieldable and bendable for passing through said opening, said flange part being clamped in place at the inside of the casing by the inflated bag.

2. In combination with an inflatable bag having an inflation nozzle and a casing for the bag having therein a circular opening to register with the nozzle, a unitary closure device comprising a plug part for sealing the nozzle, a circular disc part for closing said opening, and a peripheral flange part at the inner side of the disc part flexible throughout so as to be yieldable and bendable for passing through said opening, and being clamped at the inside of the casing by the inflated bag.

3. A unitary closure device in common for a casing having an opening therein and for an inflatable bag within the casing having an inflation nozzle registering with said opening, comprising an outer disc part for closing said opening, a thinner inner disc part of flexible material having a central opening therein secured upon the inner face of the outer disc part and projecting peripherally therefrom to form a flexible flange yieldable and bendable throughout for passing through the opening in the casing and to be clamped at the inside of the casing by the inflated bag, and a plug part for sealing the nozzle passing through the central opening in the flange-forming inner disc and having a head secured between said discs.

4. A unitary closure device in common for an inflatable bag having an introvertible inflation nozzle and for a casing for the bag having therein an opening to register with the nozzle, comprising a disc part for closing said opening, a plug part to enter and close the nozzle, a tubular flange part to fit over the outer end of the nozzle and to fit within the introverted portion of the nozzle, and a flange part projecting peripherally from the disc part adjacent its inner side and flexible throughout so as to be yieldable and bendable for passing through the opening in the casing and to be clamped at the inner side of the casing by the inflated bags.

5. In combination with an inflatable bag having an inflation nozzle and a casing for the bag having therein an opening to register with the nozzle, a closure device for said opening comprising a disc part to close said opening, a peripheral flange part on the disc part adjacent its inner side and flexible throughout to be yieldable and bendable for passing through said opening and to be

clamped at the inside of the casing by the inflated bag, and a flexible elastic attaching strip extending from the periphery of said flange and secured at its outer end to the casing at the inner side thereof.

6. A unitary closure device in common for an inflatable bag having an inflation nozzle and for a casing for the bag having therein an opening to register with the nozzle, comprising a plug part to close the nozzle, a disc part to close the opening in the casing, a

peripheral flange part on the disc part adjacent its inner side and flexible throughout to be yieldable and bendable for passing through said opening, and a pair of flexible ¹⁵ elastic attaching strips extending radially from said flange at separated points and adapted to have their outer ends secured to the casing at its inner side.

In witness whereof I have hereunto set my ²⁰ hand.

ARCHIBALD NIELD.
